METHOD OF MULTIPLE POINTING STONE CHISEL

Original Filed April 25, 1930

Inventor
Putnam P. Bicknell

By
E. S. Grafton
Attorney

In this operation the end of the portion B is forced against the channelled edge of the disc 11 so that the mid-angle of the W-shaped channel bears on the center line of the end and perpendicular to the sides of the stock. This forms in the end of the stock a central V-shaped valley and inclined outer walls. The stock is then turned 90° and again brought against the disc and these steps repeated until the points P are formed at the respective corners of the bar as in Figs. 1 and 2. Such points are symmetrical and of great strength. They may be formed at a red heat with rapidity and convenience.

The edges of the outer walls or flanges 11' of the swaging disc 11 are of a width or spacing to receive the heated end of the stock to be worked upon, so that there can be no lateral bending or displacement of the metal outside of the tool when the same is first thrust against the swaging disc, or of the teeth as they are developed. As shown in Fig. 4, the disc is provided with a W-shaped edge, which, acting on the hot stock by lateral simultaneous pressure on opposite pairs of faces or potential teeth sides, tends to draw the same forward into the V-shaped channels between the flanges 11' and 11" to produce the inclined outer walls and V-shaped valleys in the stock. The stock when pointed is somewhat longer than it was before being pointed, there has been practically no loss of stock, and the resulting points are of uniform mass and strength and are all exactly positioned with reference to each other on the bar B.

The chisel shank S may be supported on any suitable rest as at 14 and forced as desired axially in the direction of the arrow. These parts are only simply indicated as the machine may be of any simple design.

While the tool discussed is of the conventional four point type, it will be understood that the number of teeth or points might be varied and their shape changed, all without departing from the spirit of my invention.

What I therefore claim and desire to secure by Letters Patent is:

1. That method of forming the four pyramidal points of a four point stone chisel of square stock cross section which consists in heating the end to be pointed to workable condition, in drawing the points endwise of the bar by successive

relative traversings of a rotating forming die at alternating right angle positionings of the stock applied with pressure diametrically of the die edge, said die edge having peripheral channels and inclined channel walls of the cross section of the ultimate pyramidal point pairs, whereby the points are progressively separated down to their common base plane while their individual apices are simultaneously drawn out away from said base plane to the bottom of the die channels by the opposed resultant pressures of the inclined channel side walls upon opposite point faces in pairs during said successive traversings in alternate lines of movement at right angles to each other.

2. That method of forming the four pyramidal points of a four point stone chisel of square stock cross section which consists in heating the end to be pointed to workable condition, in drawing the points endwise of the bar by successive relative traversings of a rotating forming die at alternating right angle positionings of the stock applied with pressure diametrically of the die edge, said die edge having peripheral channels and inclined channel walls of substantially W-shaped cross section, whereby the points are progressively separated down to the common base plane of the point group while their individual apices are simultaneously drawn out away from said base plane to the bottom of the die channels by the opposed resultant pressures of the inclined channel walls upon opposite faces of the point pairs during said successive traversings in alternate lines of movement at right angles to each other.

3. That method of forming a chisel point which consists in heating the end to be pointed to workable condition, in drawing the point endwise of the bar by successive relative traversings of a rotating forming die at alternating right angle positionings of the stock applied with pressure diametrically of the die edge, said die edge having a peripheral channel having inclined walls of the cross section of the ultimate pyramidal point, whereby the point is drawn out and away from said base plane to the bottom of the die channel by the opposed resultant pressures of said inclined channel walls to the desired pyramidal contour of the finished point.

50 PUTNAM P. BICKNELL.
